United States Patent Office.

AMOS CUTTER, OF CHELSEA, MASSACHUSETTS.

Letters Patent No. 77,005, dated April 21, 1868.

IMPROVEMENT IN SHUTTER-FASTENINGS.

The Schedule referred to in these Letters Patent and making part of the same.

TO ALL WHOM IT MAY CONCERN:

Be it known that I, AMOS CUTTER, of Chelsea, in the county of Suffolk, and Commonwealth of Massachusetts, have invented a new and useful Improved Blind-Catch; and I hereby declare the following to be a full, clear, and exact description thereof, which will enable others to make and use my invention, reference being had to the accompanying drawings, forming part of this specification, in which is shown a front view of my invention.

The object of my invention is to produce a blind-catch easily manipulated, and conveniently reached when the blind is either open or closed.

To obtain this result, I so arrange my catch that it may upon the inside of the blind when the same is shut, and outside when thrown back or opened.

At $a a'$, in the drawings, are represented two bent arms, hinged upon a pivot at b . The lower ends of these arms are flattened, and so contrived as to close tightly over the shoulders, seen at h , on the spike c , being kept in that position by the spring d . Two spikes like that shown at c are used, one of which is attached to the window-sill, and the other driven into the side of the house, at a convenient distance from the window. A hole is made in the lower bar of the blind, shown in dotted lines at f , through which hole the spikes c pass. Over this hole the catch is placed, so as to cover the same, and is securely fastened in this position by a staple placed below the pivoted joint. The staple is shown at g . Two pins $h h'$ prevent the jaws $m m$ from being forced too far apart when the blind is opened or closed. The staple g , from its position, also assists in preventing this.

The operation of my invention may be immediately seen. By pressing together the arms $a a'$, the jaws $m m$ will open sufficiently to release them from the shoulders $h h'$, and the blind may be thrown back or drawn to.

Upon reaching the second spike, the momentum of the blind will enable it to pass over the sloping point of the same to the shoulders $h h'$, where it will be securely held without further attention.

The arms $a a'$ projecting above the bottom bar of the blind, will enable them to be readily grasped by the thumb and finger. The catch, which may be plated, if desired, will have a neat and attractive appearance.

I do not claim the arrangement of the levers, recesses, projections, and a spring in the manner exhibited in Daniel B. Randall's patent, October 31, 1865, No. 50,775. This arrangement is different from mine, the devices being fastened to the lower edge of the blind, whereas mine is fastened to the side of the lower part of a blind, so as to be on the inside when the blind is shut, and the outside when open, the spike c , in order to engage the jaws $m m$, either when the blind is open or shut, being compelled to pass through a hole in the bar, which hole is indicated in the drawings by dotted lines. The operation is also different. Increased durability is also imparted to the device by the staple g .

What I claim as my invention, and desire to secure by Letters Patent, is—

The arrangement, upon the side of the lower bar of a blind, of arms $a a'$, jaws $m m$, spring d , pivot b , staple g , and hole f for a blind-catch, in combination with the two horizontal spikes c , one driven into the wall of the house, and the other into the window-sill, so that said catch shall operate to hold the blind, when either open or closed, by one set of jaws, in the manner herein set forth.

AMOS CUTTER.
